UNITED STATES PATENT OFFICE.

HORACE W. SEVERANCE, OF CHICAGO, ILLINOIS, ASSIGNOR TO WILSON-JONES LOOSE LEAF COMPANY, A CORPORATION OF ILLINOIS.

FLEXIBLE FOLDER.

Application filed April 24, 1922. Serial No. 556,144.

To all whom it may concern:

Be it known that I, HORACE W. SEVERANCE, a citizen of the United States, and a resident of the city of Chicago, in the county of Cook and State of Illinois, have invented certain new and useful Improvements in a Flexible Folder; and I do hereby declare that the following is a full, clear, and exact description of the same, reference being had to the accompanying drawings, and to the numerals of reference marked thereon, which form a part of this specification.

This invention relates to a flexible folder adapted for retaining records not frequently disturbed.

A growing need has arisen for a handy flexible folder in which corporation statements, minutes of meetings, briefs, form letters, and other printed or written matter may be kept in quasi-permanent form, and in which publication or merchandise samples may be carried and exhibited to the trade. The old form of ring book or post binder would not suitably serve such a purpose since in the first place they would be too cumbersome and bulky, and in the second place the rings or posts would soon tear the slots in the loose leaves or samples if the book or binder were used or carried around and exhibited to any extent.

It is accordingly an object of this invention to provide a flexible folder in which sheets or samples may be retained in quasi-permanent form, which occupies but little space if filed away, which may be used as a handy reference container and conveniently kept in a desk, and which is adapted to be readily carried around and exhibited without danger of tearing or mutilating the contents.

With these and other objects in view which will become more apparent in the following description and disclosures, this invention comprises the novel structure hereinafter described and more particularly pointed out and defined in the appended claims.

In the accompanying drawings, which illustrate a preferred embodiment of this invention and in which similar reference numerals refer to similar features in the different views:

Figure 1 is a perspective view of my folder containing some loose leaves.

Figure 2 is an enlarged fragmentary inner plan view with the loose leaves lying upon the right hand side.

Figure 3 is a view similar to Figure 2, but with the leaves lying upon the left hand side.

Figure 4 is an enlarged fragmentary section on the line 4—4 of Figure 2.

Figure 5 is an enlarged fragmentary section on the line 5—5 of Figure 2.

In referring now to the drawings which illustrate a preferred embodiment of this invention, the reference numeral 1 designates a flexible folder or cover preferably formed by folding a suitable piece of pliable or imitation leather upon a center line thereof. A flexible leaf retainer 2 consisting preferably of a strip of pliable or imitation leather is hinged at substantially its longitudinal center line to the inner side 75 of the crease of the folder, and extends substantially to the ends thereof. The strip is sufficiently wide to form suitable side flaps 2^a between which sheets or loose leaves are adapted to be secured by some means. 80 While it is immaterial how the leaf retainer 2 is hinged to the crease of the folder, in the present instance, it has been shown as sewed along the center line 3. The object of thuswise hinging the leaf retainer 85 2 to the folder is for the purpose of allowing the retainer to freely swing laterally upon its hinge connection independently of the folder when the same is open or being opened, so that the action produced by opening and closing the folder will not disturb or stress the punctured and retained ends of the sheets or tend to tear or mutilate the same.

The means for securing the loose sheets 95 between the flaps 2 comprises preferably a plurality of adjustable leaf retaining studs which extend through suitably spaced apertures in the side flaps. Each stud comprises a pair of headed members 4 and 5, the member 4 being provided with an externally threaded shank and the member 5 being provided with an internally threaded shank into which the member 4 is adapted to be adjustably screwed.

The sheets 6 which it is contemplated shall include any loose leaves, samples, form letters, or the like, and which are adapted to be retained between the flaps 2^a are punched adjacent their inner margins with apertures 110

corresponding to the apertures in the flaps 2^a and similarly spaced, and in assembling these sheets, they are placed with their punched margins between the flaps 2^a with 5 their apertures registering with the apertures in the flaps. The shanks of the members 5 are then inserted through the registering apertures from one side of the assembled sheets, and the shanks of the members 10 4 are inserted in said apertures from the other side of the assembled sheets and screwed into the shanks 5, whereby the two heads of each stud may be drawn together to firmly bind or clamp the sheets between the 15 flaps. To insert additional sheets, it is only necessary to unscrew the members 4 and turn the flap upon that side in a downward direction to admit the additional sheets to be placed upon the shanks of the members 5, 20 as is obvious.

From the foregoing, it is apparent that the apertured margins of the loose sheets are protected by the side flaps between which they are held and as the flexible retainer 2 25 can readily swing from side to side upon its hinge connection to the folder causing the bound or retained sheets to move as a unit therewith independently of the folder, there is slight liability of the loose sheets being 30 torn at their apertures, as is the case where the sheets are disturbed through the opening and closing of a folder or binder to which the leaves are directly attached by means of rings or posts over which the loose sheets 35 can individually move during the operation or use of the binder. It is hence obvious that such a folder is highly adaptable for 40 use as a sample holder which must be carried around for exhibiting purposes. It is likewise admirably adapted for use in any profession for containing form letters or any data to which reference may occasionally be made and to which it may be desirable at times to add additional sheets. The folder

accordingly possesses substantially all the 45 advantages of a permanently bound flexible volume with the added advantage that additional sheets may be added thereto or taken therefrom.

I am aware that many changes may be 50 made, and numerous details of construction may be varied through a wide range without departing from the principles of this invention, and I therefore do not purpose limiting the patent granted, otherwise than 55 necessitated by the prior art.

I claim as my invention:

1. In a folder, a flexible cover, a flexible strip substantially co-extensive with the length of the cover secured interiorly of said 60 cover along substantially the center line of said strip whereby side flaps are provided and adjustable means extending through said flaps adapted for retaining the margins of sheets therebetween. 65

2. A folder comprising a one-piece flexible material folded upon a center line, a flexible leaf retainer substantially co-extensive with the folded length of said cover hinged along said center line of said folder, 70 said retainer comprising side flaps and adjustable means extending through said side flaps for retaining sheets therebetween.

3. In a folder, a piece of flexible material folded upon a center line, a flexible strip of 75 material extending lengthwise of the folder and hinged along said center line interiorly of the folder to provide expandable side flaps and adjustable telescopic means extending through said flaps for retaining sheets there- 80 between.

In testimony whereof I have hereunto subscribed my name in the presence of two subscribing witnesses.

HORACE W. SEVERANCE.
